A sealed hollow capsule having inner and outer ends and a side wall contains a pair of electric contacts spaced lengthwise of the capsule, the outer end of which supports one of the contacts. The side wall has an annular groove in it reducing the thickness at that point to a thin band that is compressible to reduce its width when a predetermined pressure is exerted against the outer end of the capsule so that one contact will engage the other contact. The switch is especially suitable for closing an electric circuit connected with electrical firing means in an explosively actuated cable cutter.

WATER PRESSURE ACTUATED ELECTRIC SWITCH FOR CABLE CUTTER

There are situations in which a ship is being towed or held in position by another ship, where it is desirable to cut the tow cable immediately upon the occurrence of a nearby underwater explosion. If this is not done, the force of the explosion may cause the ships to put such tension on the cable as to cause it to break and snap back toward the ships, where it may cause damage or injury. In other situations it is desirable to lower an object through deep water by means of a cable, and to release the cable from the object after it has reached the desired depth so that the cable can be recovered. This has been difficult to do heretofore.

It is among the objects of this invention to provide an electric switch which is closed by water pressure, which can operate a cable cutter, which will be closed by surge pressure caused by an underwater explosion, or which can be calibrated to close at a specified water depth if allowed to sink through the water. Another object is to provide a cable cutter controlled by such a switch.

The preferred embodiment of the invention is illustrated in the accompanying drawings, in which

FIG. 1 is a side view of the cable cutter and switch hanging from a cable;

FIG. 2 is a fragmentary enlarged vertical section taken on the line II-II of FIG. 1;

FIG. 3 is an enlarged vertical section of the switch; and

FIG. 4 is a similar view showing the switch closed.

Referring to FIG. 3 of the drawings, a pair of electric switch contacts 1 and 2 are rigidly mounted inside of a sealed capsule 3 having inner and outer ends connected by a side wall. The inner contact 2 may be supported by the capsule in any suitable manner, such as by an insulating plug 4 sealed in an axial opening in the inner end of the capsule. The other contact is supported by the outer end of the capsule a predetermined distance from the inner contact. To allow this distance or gap to be adjusted, the outer end of the capsule includes a screw 5 that supports the outer contact. By turning that screw, the gap can be adjusted. The side wall of the capsule is provided with an annular groove 6 that reduces the thickness of the wall in that area to a thin band that is easily deformed in a manner to be described presently.

The capsule 3 is mounted in an axial socket 10 in the outer end of a metal housing 11. The inner end of the capsule is encircled by a sealing ring 12. From the inner end of the socket a short passage 13 extends into an axial bore 14 in the inner end of the housing. This bore contains an insulating ring 16 engaged by a rubber flange 17 on the end of an electric cord 18. In this flange the inner contact 2 is connected with one of the wires 19 in the cord. The other wire 20 is soldered to a split metal ring 21 encircling the cord between flange 17 and a second rubber flange 22. The ring engages the encircling housing and is pressed tightly against it by the portion of the cord inside the ring. That portion expands when the two rubber flanges are clamped tightly between insulating ring 16 and a flanged bushing 23 that is held in place by a nut 24 screwed onto the inner end of the housing. The outer contact 1 is electrically connected through the metal capsule 3 and housing 11 with the metal ring 21 and wire 20.

When this switch is submerged in water and the water pressure against the outer end of the capsule becomes great enough, the water will move the outer end of the capsule inwardly to cause the thin metal band of its side wall to compress, as shown in FIG. 4. The band compresses by bending radially inward or outward upon itself. When this occurs, the outer contact 1 moves into engagement with the inner contact 2 to close the switch. In order to increase the effective area against which the water pressure acts, a cup-like pressure cap 26 is slidably mounted on the outer or lower end of housing 11 around the capsule. The end wall of the cap is spaced from the end of the housing, preferably by having the capsule project from the housing, or in an equivalent manner by providing the cap with a central projection small enough to enter the housing socket 10. The cap is held against the capsule by means of circumferentially spaced headed pins 27 screwed into the cap and slidably mounted in holes through a flange 28 encircling the housing and spaced from the inner or upper end of the cap. Water is prevented from entering the space between the outer end of the housing and the cap by a sealing ring 29 mounted in a groove, such as in the periphery of the housing. It will be seen that water pressure against the outer end face of the cap sufficient to overcome the resistance of the thin band in the capsule wall will push the outer end of the capsule inwardly, causing the thin band to collapse and thereby allowing the two contacts to engage each other.

Although the electric switch disclosed herein can be used for various purposes, it is especially suitable for firing an explosively actuated cable cutter, as shown in FIGS. 1 and 2. Such a cutter may include a frame 30 provided with a barrel in which a chisel 31 is slidably mounted. The frame has a recess 32 in one side to permit a cable 33 to enter it between the chisel and an anvil 34 in the front end of the frame. The frame can be locked onto the cable by means of a retractable sleeve 36 slidably mounted on the frame and urged forward across the entrance to recess 32 by a coil spring 37 that engages a cartridge holder 38 screwed into the rear end of the frame behind the chisel. An explosive charge or cartridge 39 is disposed in the holder and contains a hot wire primer 40. This primer is connected by a wire 42 with a contact 43 on the back of an insulating member 44 disposed in the rear end of the cartridge holder. The contact engages a battery 45 in the front end of a tube 46 that is clamped against the rear end of the cartridge holder by means of a threaded collar 47. The tube is filled with enough batteries to provide the desired voltage. The primer is also connected by a wire 48 to a split metal ring 49 that tightly engages the surrounding wall of the cartridge holder.

At the opposite end of tube 46 one of the batteries engages a contact 51 that is electrically connected by a wire 52 to a filter 53 screwed into a grounding ring 54. The lower end of the filter is in electrical contact with a pin 55 that projects into a socket 56 on the end of wire 19 in the electric cord. This end of the cord is formed like the other end and is held in a coupling 57 screwed onto the rear end of the battery tube. The other wire 20 of the cord is electrically connected with the coupling through a split metal ring 58 between two rubber flanges 59 and 60 on the cord. A flanged bushing 62, held in place by a nut 63 screwed onto the lower end of coupling 57, presses against flange 60.

To provide for severing a tow cable between two ships, the cutter can be hung on the cable with the electric switch hanging down into the water as shown in FIG. 1. The cord 18 is long enough to allow the switch to be submerged a considerable distance, such as fifty feet for example. An underwater explosion that causes a surge pressure great enough to move housing 11 and cap 26 toward each other will close the switch contacts 1 and 2 and thereby fire the cutter. This will cause the chisel 31 to sever the cable 33.

Instead of being used for the purpose just described, the cutter may be attached to a cable that is to lower an object to the ocean bed, where it is to be left. In order to be able to retrieve the cable, the cutter is attached to it close to the object being lowered and the switch is set to operate at the water pressure existing near the ocean bed. When the switch reaches that depth, the water pressure is great enough to collapse the thin wall portion of capsule 3 and thereby close the switch contacts to fire the cutter. A short cord 18 would generally be used so that the switch would be close to battery tube 46. Also, instead of the cable cutter being provided with its own batteries, a battery located above the water could be used by connecting it by means of a long electric cord to the pressure-actuated switch, which would be electrically connected with the electric primer 40.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A water pressure actuated electric switch comprising a sealed hollow capsule having inner and outer ends and a side wall, a pair of electric contacts in the capsule spaced lengthwise thereof, one of the contacts being supported by the outer end of the capsule, said side wall having an annular groove therein reducing the

thickness of a portion of the side wall to form a thin band in the wall, and said band being compressible to reduce its width when a predetermined pressure is exerted against said outer end of the capsule, whereby to permit said one contact to engage the other contact, wires electrically connected with said contacts and adapted to be electrically connected with a source of electricity, and an electrically fired cable cutter in series with one of the wires.

10 2. A cable cutter comprising a cutting member, an explosive charge for actuating said member, electrical firing means for said charge, a normally open electric circuit containing said firing means, and a normally open water pressure actuated switch in said circuit for closing it when the switch is exposed to a predetermined water pressure.

3. A cable cutter according to claim 2, including a frame for said cutting member and explosive charge and firing means, said circuit including batteries, and a sealed housing for the batteries rigidly connected to the frame.

4. A cable cutter according to claim 2, in which said switch includes a sealed hollow capsule having inner and outer ends and a side wall, a pair of electric contacts in the capsule spaced lengthwise thereof, one of the contacts being supported by the outer end of the capsule, said side wall having an annular groove therein reducing the thickness of a portion of the side wall to form a thin band in the wall, and said band being compressible to reduce its width when a predetermined pressure is exerted against said outer end of the capsule, whereby to permit said one contact to engage the other contact.

35 5. A cable cutter according to claim 4, including a housing containing said capsule with the outer end of the capsule projecting from the housing, and a cup-like pressure cap engaging said outer end and slidably mounted on said housing in sealing engagement therewith.
